SUCTION NOZZLE

Gustaf Erik Björkman, Saltsjö-Nacka, Sweden,
assignor to Electrolux Corporation, Dover, Del.,
a corporation of Delaware

Application March 19, 1937, Serial No. 131,752
In Germany March 21, 1936

8 Claims. (Cl. 15—155)

My invention relates to suction nozzles and more particularly to a so-called duplex nozzle in which either a concentrated flow of air, or a more widely distributed flow may be obtained. 5 A widely distributed flow of air is preferable for ordinary cleaning in order that a maximum area may be cleaned, while a concentrated flow is desirable when it is necessary to remove objects, such as threads and the like, which adhere strongly to the surface being cleaned.

In accordance with my invention such a nozzle is provided with means movable in a direction parallel to the lengthwise extent of the nozzle for altering the flow of air. Normally, in cleaning, the nozzle is moved back and forth over a surface in a direction substantially at right angles to its lengthwise extent. By having the valve controlling means movable in a direction substantially at right angles to the normal movement of the nozzle, likelihood of accidental shifting of the valve is greatly reduced. In accordance with the preferred embodiments of my invention, the valve may be shifted by moving the nozzle lengthwise against some object, such as the operator's foot or a convenient piece of furniture. However, should the nozzle accidentally strike an object during its normal back and forth movement, the valve would not be actuated.

Further objects and advantages of my invention will be apparent from the following description considered in connection with the accompanying drawings which form a part of this specification, and of which—

Fig. 1 is a view of one embodiment of my invention shown in connection with a vacuum cleaner unit;

Fig. 2 is a cross-sectional view of the nozzle shown in Fig. 1, but on a larger scale;

Fig. 3 is a bottom view of the nozzle shown in Fig. 2;

Fig. 4 is a top view, partially broken away, of the nozzle shown in Figs. 2 and 3;

Fig. 5 is a cross-sectional view taken on the line 5—5 of Fig. 4;

Fig. 6 is a perspective view of a portion of the nozzle, including a valve member;

Fig. 7 is a cross-sectional view of a second embodiment of my invention;

Fig. 8 is a bottom view of the nozzle shown in Fig. 7;

Fig. 9 is a cross-sectional view taken on the line 9—9 of Fig. 7;

Fig. 10 is a cross-sectional view of a third embodiment of my invention;

Fig. 11 is a cross-sectional view taken on the line 11—11 of Fig. 10; and

Fig. 12 is a cross-sectional view, on an enlarged scale, showing a detail of construction.

Referring more particularly to Figs. 1 through 6, reference character 10 designates a vacuum cleaner unit, provided with the usual air flow producing means and dust separating means. Connected to the inlet of unit 10 is a flexible hose 11, the other end of which is connected to 10 a hollow handle 12, which in turn is connected to the suction nozzle designated generally by the reference character 13.

Nozzle 13 includes an elongated body 14 formed with surface contacting lips 15 surrounding and 15 defining an elongated suction opening 16. Secured to and forming the top of body 14 is a member 17. The central part of member 17 has a semi-cylindrical shape, as is shown at 18, this part being provided with an opening 19. A hollow connection piece 20 has a flared lower end 21 which is pivotally secured to cylindrical portion 18 by means of holding members 22 which are secured to body 14 by means of screws 23. The other end of member 20 is formed with a 25 cylindrical or slightly tapered bore 24 which is adapted to receive the end of hollow handle 12.

The forward central part of body 14 is formed with a groove 25 having a lengthwise extent which is considerably less than opening 16, as 30 will be apparent particularly from Fig. 3. A portion 26 of member 17 extends into slot 25 and defines a small suction opening 27 which communicates at its inner end with the space within cylindrical portion 18. The nozzle body 35 is formed with a port 28 which connects elongated suction opening 16 with this same space.

Slidably mounted in body 14 on either side of suction opening 16 are rods 30 and 31. These rods extend beyond the ends of the body 14 40 and are there connected together by means of cross-pieces 32. As shown particularly in Fig. 3, the length of rods 30 and 31 is such that, if one cross-piece 32 bears against the end of body 14, the other cross-piece is spaced from the body. 45 Member 17 overhangs at each end of the body member 14, as is shown at 33 by an amount sufficient to substantially cover the cross-piece 32 when the latter bears against the end of the body 14 and to cover the space between them 50 when they are separated.

Rotatably mounted on rod 30 is a valve member 34. Movement of the valve member with the rod is prevented by means of shoulders 35 formed in the body 14. The valve member is 55

formed with a helical slot 36 which is engaged by a pin 37 rigidly secured to the rod. Consequently, straight line motion of the rod causes turning of the valve member. The valve member is formed with a flat face 38 which closes port 28 when the valve member is in one extreme position, and is formed with a curved face 39 which is adapted to seat against the semi-cylindrical portion 18 and thus closes inlet opening 27 when the valve is in its other extreme position.

A spring member 40 is provided for holding the rods 30 and 31, and hence the valve 34, in either of their extreme positions. One end of the spring 15 is received within a notch 41 formed in body 14, while the other end of the spring is forked and engages a portion of reduced diameter 42 formed on rod 31. Inasmuch as spring 40 is maintained under compression it tends to hold the rod 31 in 20 either of its extreme positions.

In operation, nozzle 13 is moved forward and backwards over a surface to be cleaned by means of handle 12. The vacuum cleaner unit 10 causes air to flow inwardly through the nozzle, through 25 the hollow handle, and hose 11 to the unit. With the valve 34 in the position shown in Fig. 2, air is admitted to the nozzle through the elongated opening 16 and the port 28. The curved portion 39 of the valve is seated against member 18 and 30 prevents inflow of air through suction opening 27. With the nozzle in this condition, it is capable of covering a maximum amount of surface on each 35 stroke, the air flow being distributed over the entire length of suction opening 16. In the event that a thread or other object which adheres with considerable force to the surface is encountered, it may be removed by shifting the valve 34 so as to close port 38 and to permit inflow of air through opening 27. Inasmuch as opening 27 40 is smaller than opening 16, a more concentrated flow of air is obtained, which is able to remove the thread.

The valve is shifted by moving members 32 relative to the nozzle body. This may be accomplished by moving the nozzle sideways against the operator's foot or against any other stationary object, or the member 32 may be kicked by the operator. In either event, straight line movement takes place between the rods 30, 31 and 50 the nozzle body which results in a turning of the valve 34. In order to return the valve to its original position, the rods are moved in the opposite direction. Inasmuch as one of the other members 32 always projects beyond the overhanging portion 33 of member 17, it is always 55 apparent in which direction the rod should be moved in order to alter the position of the valve. If desired, a legend or the like may be placed on the top of the nozzle, adjacent one end to indicate that the valve is in a certain position when the member 32 at that end projects beyond portion 33.

In the embodiment shown in Figs. 7 through 9, the valve member itself constitutes the member 65 which is slidable with respect to the nozzle body. As shown, the nozzle body 14 is formed with an elongated opening 16, which communicates with the interior of the body through a plurality of ports 50 spaced an equal distance apart and arranged in a straight line. The small nozzle opening 27 communicates with the space within the nozzle body through a port 51 which is disposed in a plane at substantially right angles to the plane of ports 50.

Valve member 52 includes a flat plate-like

member formed with a plurality of openings 53. These openings correspond in size, number and spacing to the ports 50. The valve member also includes a vertical portion 54 which is arranged to cooperate with port 51. The ends of the valve 5 member 52 extend beyond the ends of body 14 and are connected to cross-pieces 32.

With the valve member in the position shown in the figures, openings 53 are out of registry with ports 50 and consequently the suction opening 16 is cut off from the interior of the nozzle. Portion 54 of the valve, on the other hand, is to one side of port 51 and consequently communication is established between the small suction opening 27 and the interior of the nozzle. 15 The nozzle is now in condition to remove threads and similar objects.

If the valve 52 is moved to the right, as viewed in Figs. 8 or 9, portion 54 covers port 51, while openings 53 come into alignment with ports 50. 20 Consequently, small suction opening 27 is closed, while the large opening 16 is connected to the interior of the body through the ports 50 and openings 53.

In the embodiment shown in Figs. 10 through 12, a nozzle body 60 is formed with a cylindrical portion 61 in which is slidably and rotatably mounted a hollow cylindrical valve member 62. Rigidly secured to the valve member and communicating with the interior thereof is a connecting piece 63 to which may be connected the hollow handle 12. It will be noted that the length of valve member 62 is less than the interior length of cylindrical portion 61.

Nozzle body 60 is formed with three similar 35 aligned openings 64, 65 and 66, while the valve member 62 is provided with openings 67 and 68. As will be noted opening 68 is of the same axial length as opening 66, while opening 67 is of sufficient axial length to be able to span both openings 64 and 65. Thus, with the parts in the position shown in Fig. 11, openings 64, 65 and 66 are all in communication with the interior of valve member 62 and hence air is drawn in through all of these openings. This gives a distributed flow of air which is to be preferred for ordinary cleaning. In order to obtain a concentrated flow, the valve member 62 is moved axially with respect to the nozzle in a direction toward the right, as viewed in Fig. 11. This causes openings 64 to be closed by the left hand end of the valve member while opening 66 is closed by that portion of the valve member between openings 67 and 68. Opening 65 alone remains in communication with the interior of the valve member, this communication being established through a portion of opening 67. Thus, all the air is caused to flow through opening 65 which results in a concentrated flow which is capable of removing threads and the like. 60

The circumferential extent of openings 67 and 68 in the valve member is such that the valve member may be rotated with respect to the rest of the nozzle without affecting substantially the flow of air. Thus, the handle 12 may be raised 65 and lowered to suit the convenience of the operator in manipulating the nozzle under furniture or the like.

In order to prevent accidental shifting of the valve member, cylindrical member 61 may be provided at either of its ends with a button 70, as is shown particularly in Fig. 12. The ends of valve member 62 are formed with openings 71 into which buttons 70 may extend. A resilient member 72 is secured within the valve member and 75

around each opening 71 and is adapted to releasably engage button 70. Thus, the valve member is retained in either of its extreme positions. In order to shift the valve member, the end of the 5 nozzle is held stationary, as by the foot of the operator or as by being placed against a convenient wall or piece of furniture, and the handle 12 is moved sideways with respect to the nozzle. This causes the valve member 62, which is rigidly secured to the connecting member 63, to be moved sideways, one of the buttons 70 being released from the corresponding resilient member 72 at the beginning of the movement, and the other button engaging the other resilient member 15 at the other end of the valve at the end of the movement.

While I have shown several more or less specific embodiments of my invention, it is to be understood that this has been done for purposes of illustration only and that the scope of my invention is not to be limited thereby, but is to be determined by the appended claims viewed in the light of the prior art.

What I claim is:

- 25 1. In a suction nozzle, an elongated body adapted to be moved transversely with respect to its length over a surface to be cleaned, said body being formed with a plurality of suction openings, valve means for controlling flow through said 30 openings to vary the total effective inflow area, and structure extending outside of said body and movable in a straight line in one direction lengthwise relative to said body for moving said valve so as to increase said total inflow area and movable 35 in a straight line in the opposite direction for moving said valve so as to decrease said total inflow area, the end portions of said structure being extendible beyond the ends of said body so as to be accessible for movement in either direction.
- 40 2. In a suction nozzle, an elongated body adapted to be moved transversely with respect to its length over a surface to be cleaned, said body being formed with a large suction opening and a smaller suction opening, a valve member pivotally 45 mounted in said body and turnable to selectively render either of said openings operative, a member carried by said body and movable in a straight line parallel to the lengthwise extent of said body for turning said valve, and means for converting 50 the straight line motion of the last mentioned member into rotary motion of said valve member.
- 55 3. In a suction nozzle, an elongated body adapted to be moved transversely with respect to its length over a surface to be cleaned, said body being formed with a large suction opening and a smaller suction opening, valve means for selectively rendering either of said openings operative, and structure carried by said body and movable in a straight line parallel to the lengthwise extent 60 of said body for operating said valve means, the end portions of said structure being extendible beyond the ends of said body so as to be accessible for movement in either direction.
- 65 4. In a suction nozzle, an elongated body adapted to be moved transversely with respect to its length over a surface to be cleaned, said body being formed with a large suction opening and a smaller suction opening, valve means movable be-

tween two extreme positions for selectively rendering either of said openings operative, and means carried by said body and movable in a straight line parallel to the lengthwise extent of said body for operating said valve means, and means for yieldably retaining said valve means in either of said extreme positions and for urging said valve means out of intermediate positions. 5

5. In a suction nozzle, an elongated body adapted to be moved transversely with respect to its length over a surface to be cleaned, said body being formed with a large suction opening and a smaller suction opening, a rod slidably mounted in said body and movable in a straight line parallel to the lengthwise extent of said body, a 15 valve member pivotally mounted on said rod and held against movement therewith, said valve member being pivotable to open and close the respective openings, said valve member being formed with a helical slot, and a pin carried by 20 said rod and engaging said slot whereby straight line movement of said rod causes turning movement of said valve member.

6. In a suction nozzle, an elongated nozzle body adapted to be moved in a direction transverse to its length over a surface to be cleaned, said body being formed with dissimilar suction openings, and a valve member carried by said body and 25 slidably in a direction parallel to the length of said body for selectively rendering either of said 30 openings operative, the ends of said valve member being extendible beyond the ends of said body, whereby the valve member is accessible for operation.

7. In a suction nozzle, an elongated nozzle body adapted to be moved in a direction transverse to its length over a surface to be cleaned, said body being formed with dissimilar suction openings communicating with valve ports within said body located in angularly disposed planes, and a valve 40 member having portions located in similarly angularly disposed planes and slidably in said body in a direction parallel to the length of the body for selectively closing and opening the respective 45 ports, said valve member being longer than said body whereby either of its ends is extendible beyond said body so as to be accessible for manipulation.

8. In a suction nozzle, an elongated nozzle body adapted to be moved in a direction at right angle to its length over a surface to be cleaned, said body being formed with a large suction opening and a small suction opening, said large opening communicating with a plurality of valve ports arranged in a straight line in said body, and said small opening communicating with an additional valve port, and a valve member having a plurality of openings corresponding in size and distribution to said plurality of valve ports and an additional opening corresponding to said additional valve port, said valve member being movable in a direction parallel to said straight line, the space relationship of said valve ports and the openings in said valve member being such that when said plurality of ports and said plurality of openings are in registry said additional port and additional opening are out of registry and vice versa. 55 60

GUSTAF ERIK BJÖRKMAN.
